UNITED STATES PATENT OFFICE.

EZRA SHOWALTER, OF MASSILLON, OHIO.

DESIGN FOR A CAR-REPLACER.

SPECIFICATION forming part of Design No. 34,291, dated March 26, 1901.

Application filed February 21, 1901. Serial No. 48,374. Term of patent 14 years.

To all whom it may concern:

Be it known that I, EZRA SHOWALTER, a citizen of the United States, residing at Massillon, in the county of Stark and State of Ohio, have invented and produced a new and useful Design for Car-Replacers, of which the following is a specification.

My invention relates to a new and useful design for car-replacers; and it consists of a block of the configuration and ornamentation shown in the accompanying drawing, in which the figure is a perspective view.

The leading feature of my design consists of a plate A, substantially parallelogram, raised in the center and having the inclined sides a and b. Upon both sides there are provided the apertures c and d, of a sufficient

width and depth to permit the block to be placed upon and over the rails of the track, thus forming a bridge. Upon the upper surface of the block A there are provided diverging grooves or guideways e, f, g, h, i, and j, which serve to guide the flanges of the wheels of the car in any desired direction.

What I claim is—

The design for a car-replacer herein shown and described.

In testimony whereof I have hereunto set my hand in the presence of two subscribing witnesses.

EZRA SHOWALTER.
